United States Patent Office

Des. 222,582
Patented Nov. 9, 1971

222,582

DISPLAY CONTAINER

Patrick Petrie, 12210 Malone St.,
Los Angeles, Calif. 90066

Filed Dec. 8, 1970, Ser. No. 26,357

Term of patent 14 years

Int. Cl. D9—03

U.S. Cl. D9—191

FIG. 2

FIG. 1

FIG. 3

FIG. 4

FIG. 5

FIG. 6

FIG. 1 is a perspective view of a display container showing my new design;

FIG. 2 is a side elevational view thereof;

FIG. 3 is a front elevational view thereof;

FIG. 4 is a rear elevational view thereof;

FIG. 5 is a top plan view thereof; and,

FIG. 6 is a bottom plan view thereof.

I claim:

The ornamental design for a display container, substantially as shown.
